UNITED STATES PATENT OFFICE.

GEORGE BOULTON, OF ROCHESTER, NEW YORK.

ATTACHMENT FOR SEWING MACHINES.

Application filed April 29, 1924. Serial No. 709,917.

The present invention relates to attachments for sewing machines, and an object thereof is to provide attachments which will permit an ordinary commercial sewing machine to lay and sew either a plain binding or a flat tape adapted to be folded around the edge of a material producing what is known as a French cord binding. Another object of the invention is to provide a construction by which either the guide for the plain binding or a flat tape may be brought readily into cooperation with the feeding plate at will, provision being made in the feeding plate for the reception of the guide for the plain binding when the latter is used, and for filling said space to provide a smooth surface over the feeding plate when the guide for the flat tape is used. A further object of the invention is to provide a construction in which a guide for a flat tape is moved out of feeding position when the presser foot for the sewing machine is elevated, means being employed for automatically holding the flat tape guide in its shifted non-operative position. A still further object of the invention is to provide a tape guide which has the guiding member removably connected to its support so that guiding members of different widths and styles may be used.

To these and other ends, the invention consists of certain parts and combinations of parts, all of which will be hereinafter described, the novel features being pointed out in the appended claims.

In the drawings:

Fig. 1 is a detail sectional view of a piece of material showing the manner in which the flat tape is laid when the French cord binding is desired;

Fig. 2 is a similar view showing the manner in which the flat tape is bent around the edge of the material to provide the French cord binding;

Fig. 3 is a similar view showing the manner in which a plain binding is secured on a piece of material;

Fig. 4 is a fragmentary front view of the sewing machine with the present improvements mounted thereon, the guide for the flat tape, as well as the filler for the pocket in the feeding plate, being shown in operative positions;

Fig. 5 is a fragmentary view showing the guide for the flat tape held in non-operative position;

Fig. 6 is a plan view of the horn showing the filler in position and the guide for the plain binding shifted to non-operative position;

Fig. 7 is another fragmentary view showing the guide for the flat tape in non-operative position;

Fig. 8 is a fragmentary end view of the machine showing the guide for the flat tape in operative position;

Fig. 9 is a section on the line 9—9 through the feeding plate showing the guide for the plain binding in position;

Fig. 10 is a perspective view of the feeding plate;

Fig. 11 is a detailed perspective view of one of the guiding members for flat tape;

Figs. 12 and 13 are two views of one of the tape guides and their support; and

Figs. 14 and 15 are two detail perspective views of the support for the tape guide, illustrated in Fig. 11.

At the present time it is customary in shoe making and some other manufacturing lines to employ two kinds of binding, one known as "French cord binding" and the other known as "plain binding." The French cord binding is made by taking a piece 1 on which the binding is to be secured and sewing a tape or binding material 2 by stitches 3 adjacent one edge of the material 1, as shown in Fig. 1, and thereafter bending the binding tape around the edge of the material 1, as shown in Fig. 2, and cementing the tape in such position. According to the plain binding, the material 1 has the binding tape 4 overlapping both sides of the material 1, as shown in Fig. 3, being secured in position by stitches 5.

Prior to this invention two independent attachments have been employed for laying the two styles of binding strips on the materials whose edges are to be bound. This required that either two separate sewing machines be employed or one attachment was required to be removed in order to place the other attachment on the sewing machine. According to this invention, the two attachments are so combined that either may be brought into use with but a few adjustments.

Referring more particularly to the illustrated embodiment of the invention, 6 indicates the arm of the sewing machine in the end of which the needle bar 7 operates, and 8 indicates the usual horn which projects below the arm which supports and feeds the

work. The end of this horn 8 has a feed plate 9 formed with an opening 10 through which the feeding devices (not shown) and the needle move. Movable on the arm 6 is the usual presser foot 11 which is moved toward and from the feed plate 9 through a lever 12 as is common in sewing machines of this type. These sewing machine parts are all old and will not be described with greater particularity.

In order to lay the French cord binding, a spool 13 is mounted to turn on a shaft 14 supported on a bracket 15 mounted on the arm 6. From this spool the tape or binding 16 leads downwardly through a guide 17 on the front of the machine and also to a slotted guide 18 which directs the tape beneath the presser foot 11. This guide 18 is preferably resiliently supported from the arm 6 and to this end a bracket 19 depends from the arm 6 preferably being secured to the arm by screws 20. This bracket is provided with two guide arms 21 and 22 through which a stem 23 on the guide 18 works. This stem also carries an abutment piece 24 and above this abutment piece and below the guide arm 21 a helical spring 26 surrounds the stem 23 and normally tends to hold the guide 18 downwardly.

In order that the guide 18 will be elevated when the presser foot 11 is elevated, an arm 27 may be extended forwardly from the presser foot and cooperate with the underside of the screw 25, thereby permitting the guide 18 to yield relatively to the presser foot while, at the same time, when the presser foot is elevated through the operation of the lever 12, the guide 18 will also be elevated.

A gravity latch 28 or other means is preferably supported by the bracket 19 being pivoted at 29 to such bracket, its lower end is bevelled at 30 so that when the presser foot is elevated the abutment 24 will engage the bevelled or lower end of the latch 28, shift the latter on its pivot and permit such latch to engage beneath the abutment in order to hold the abutment in elevated position when the presser foot is again lowered. The guide may be lowered, after the presser foot is lowered, by moving the latch 28 to disengage with the abutment 24.

Another feature of this invention is the manner of mounting the guide 18 on its support or stem 23 so that guides 18 of different types and widths may be employed. In the present instance, the guide 18 has its intake deflected upwardly at 41 so that the tape readily enters the tube. Furthermore, this guide has an internal groove 42 which adapts the guide to a tape with rib now being employed in shoe making. The discharge end of the tube is notched at 43 for the passage of the needle, so that the

tape may be fed all the way to the needle by the guide. The stem 23 has means for detachably securing the guide thereto. This means comprises a head 44 with a clamping portion 45, the head being straddled by a bifurcated or U shaped portion 46 of another clamping member which has a clamping portion 47. The two clamping portions 45 and 47 engage opposite edges of the guide 18 and a screw 48 adjustably secures the two clamping portions together while passing through the bifurcated portion 46 and into the head 44.

When the plain binding is used, the guide 18 is held in the raised position, as illustrated in Fig. 5, and the plain binding shaper lies in the position illustrated in Fig. 9. This plain binding shaper embodies a guide tube 31 having a bevelled end 32 formed with a groove 32a and supported on one end of an arm 33 which is pivoted at 34 to the frame of the machine. This arm 33 is swung over the arm or horn 8 and its end is received in a notch 35 formed in the plate 9 and acting to hold the arm 33 against swinging while, at the same time, permitting the tape 4 to issue from one end of the tube or guide 31 in proper relation to the needle opening 10 in said plate. The tape passes from any suitable supply about guide rods 37 and thence through the guide tube 31 out through the bevelled grooved end of the latter. This bevelled end gives to the tape a U shaped form in cross section and after it passes from the guide tube it passes under the needle 10', which produces the stitch 5.

In order that the notch 35 in the plate 9 will not interfere with the sewing of the flat tape 2, an arm 38 is provided which has a common pivot 34 with the arm 33 and has an end 39 formed similarly to the notch 35 to act as a filler for such notch and provided with a small groove 40 which acts to guide the needle 10'. The upper face of this filler is flush with the top face of the feed plate.

From the foregoing it will be seen that attachments have been provided which will make it possible to sew on one sewing machine either a plain binding or what is known as the French cord binding, these results being secured by attachments shifted at will into cooperative relation with the feed plate of the sewing machine. The feed plate has a pocket adjacent the opening through which the needle passes which, when the plain binding is to be sewed, receives the guide for the plain binding, and which, when the French cord binding is to be sewed, receives a filler which provides a smooth surface over which the material may travel. The guide for the flat tape which is to form the French cord binding is so connected to the presser foot that the latter will shift

the guide away from the feed plate as the presser foot is shifted away from the feed plate, provision being made whereby the guide for the flat tape may be automatically held away from the feed plate so that the presser foot may be returned to the feeding plate independently of the guide for the plain tape.

What I claim as my invention and desire 10 to secure by Letters Patent is:

1. The combination with a feed plate and a presser foot, of a guide for feeding a flat tape between the feeding plate and the presser foot, said presser foot being moved 15 independently of the guide toward the feeding plate, means for connecting the presser foot with the guide to cause the latter to move away from the feeding plate with the presser foot, and means automatically operating 20 when the presser foot is moved upwardly to hold the guide away from the feeding plate so that the presser foot may move toward the feed plate independently of the guide.

2. The combination with a feeding plate and a presser foot movable toward and from the feed plate, of a guide for feeding a flat tape between the presser foot and the feed plate, a stem extending upwardly from the 25 guide, a bracket in which said stem operates, a spring surrounding the stem, an abutment on the stem engaged by the spring to move the guide toward the feed plate, an arm on the presser foot cooperating with the abutment to move the stem away from the feed plate after the presser foot is moved away from the feed plate, and a pivoted latch 30 automatically cooperating with the abutment

to hold the guide away from the feed plate when the presser foot is moved upwardly. 40

3. The combination with a feeding plate and a presser foot movable toward and from the feed plate, of a guide for feeding a flat tape between the presser foot and the said plate, spring means normally tending to hold 45 the guide toward the feeding plate, a connection between the presser foot and the guide for moving the latter away from the feeding plate against the action of the spring means, and automatically operating means 50 for holding the guide away from the feeding plate after the guide is moved against the action of the spring by the presser foot, said means permitting the presser foot to move again toward the feeding plate in- 55 dependently of the guide.

4. The combination with a feeding plate provided with a needle opening and a pocket adjacent said opening, an arm pivotally mounted on the machine and carrying a filler for filling the pocket and providing a flush face over which a flat tape may pass, a presser foot for cooperation with the feeding plate, a guide for a flat tape movable toward and from the feed 60 plate, a connection between the presser foot and such flat tape guide for causing the latter to move away from the feed plate as the presser foot is moved away from the feed plate, and automatically operating means for 65 holding the flat tape guide away from the feed plate when such guide is moved by the presser foot, permitting the presser foot to move toward the feeding plate independently 70 of the flat tape guide.

GEORGE BOULTON.
